KNITTING MACHINE

John H. Murphy, Cohoes, N. Y., assignor to Putnam Knitting Company, Cohoes, N. Y., a corporation of New York

Application January 23, 1934, Serial No. 707,939

4 Claims. (Cl. 66—12)

This invention relates to knitting machines and particularly to circular knitting machines having vertically operating knitting needles.

The purposes of my present invention are; to provide a new and improved form of knitting machine of the type mentioned and particularly to provide a circular knitting machine where the vertically operating knitting needles are arranged in two independently operated sets preferably operated at successive feeds and to have the machine provided with further mechanism and the said needles so located and operated as to insert in the basic web a heavy proportion of terry threads and also to insert into the fabric as it is being knitted weft threads that will be so slightly curved in the fabric as knitted that after the fabric is washed and finished the weft threads will be so nearly straight as to render the completed fabric practically inelastic transversely of the wales; to provide a machine of the class described that not only has two sets of alternately operating needles so as to make a basic web formed really of two plain knitted structures independent of each other though caught or meshed together, but to have the machine also so constructed that the two sets of vertically operating needles are mounted concentrically but in circles of slightly different diameter whereby room and opportunity is afforded for not only putting in a terry thread at each feed but for accomplishing the much more difficult operation of putting a substantially straight weft thread into certain of the feeds that are also being provided with terry threads; to provide in such a machine for such an arrangement and proportion of the parts and such adjustment and combination and cooperation of the mechanism of the machine as will provide for the knitting of the said two-part basic web of sufficiently open structure and to provide for the insertion preferably in every feed thereof, (that is at each stitch of the fabric) of a terry thread having long loops drawn to one side of the fabric and to have the machine place into the fabric at all or at certain feeds and even into the same feeds where the terry threads are placed, a third set of threads called weft threads, which weft threads extend transversely of the wales with very slight curvature so that after the washing and other finishing and lateral stretching operations have been completed upon the knitted fabric the said knitted fabric will be practically free from distortion; that is practically unstretchable transversely of the wales of the stitches, notwithstanding the openness of the body of the

fabric and the looseness of the terry threads; to provide a machine of the sort described which will make not only the two-part intermeshed basic fabric but will place therein at each of the two separate sets of needle-feeds a terry thread so that a terry loop will project from each mesh of the basic web at the back of the fabric but with the terry loops of any given terry thread projecting only from alternate meshes of the fabric whereby the appreciable length of the many terry threads that are in the body of the fabric between the projecting loops will help to hold the loops of terry threads permanently in place; and further to have the construction of the machine and the cooperation of its parts such that the weft threads will be placed in the fabric as nearly straight as the character of the fabric and the operation will allow, so that as the fabric is removed from the machine and the initial contraction of the fabric takes place the weft threads will be in the form of gently undulating lines but after the finishing and lateral stretching processes have taken place the weft threads will be practically without curves and will extend transversely of the rows of stitches so as to be practically unstretchable and yet so strongly held to the body of the fabric as to make the fabric unstretchable or practically inelastic lengthwise of the weft threads; and finally to provide a machine of the construction above outlined that is durable and mechanically efficient in construction and not liable to get out of order and that will operate with regularity and effectiveness.

Further purposes and advantages of the invention will appear from the specifications and claims herein.

Fig. 1 is a vertical, radial, sectional view through one side of a knitting machine embodying this invention, parts of the cylinder and dials being broken away and the supporting means being largely omitted and the yarn cops and cop-supporting frame being omitted in order to allow the knitting mechanism proper to be shown practically full-sized.

Fig. 2 is a top or plan view of a small portion of the needle cylinder showing the alternately arranged shallow and deep needle grooves in the upper portion of the cylinder.

Fig. 3 is a horizontal sectional view of a small part of the cylinder as on line 3—3 of Fig. 4, showing the deep grooves for all needles in that zone of the needle cylinder.

Fig. 4 is a vertical sectional view on line 4—4 of Fig. 2, viz: of the cylinder on the line of a

groove that is shallow at the top of the cylinder and contains a short and outwardly-located needle.

Fig. 5 is a similar view of the cylinder but through a needle groove that is deep at the upper part of the cylinder as on line 5-5 of Fig. 2 and containing a long and inwardly-located needle.

Fig. 6 is a sectional view similar to Fig. 5 but showing the long needle in the foreground and depressed and the short needle in the next groove raised.

Fig. 7 is a developed front view partly diagrammatical of two feeds of the machine, one feed at the right where a weft thread as well as a terry thread and a needle thread are provided for the same feed and the second feed at the left where the other set of needles receive a needle thread and a terry thread but no weft thread.

Fig. 8 is a top and largely diagrammatical view showing the position of the hooks at two feeds and the tops of the two circles of needles and the position of the terry threads and the weft thread of Fig. 7 but omitting the needle threads.

Fig. 9 is a view on a greatly enlarged scale of the rear or loop side of a piece of fabric of the preferred form which this machine is designed to knit. The drawings show the fabric on a greatly enlarged scale and with the vertical rows of stitches and the lateral courses of stitches shown even more extended and the threads separated so as to more closely and definitely show the construction of the fabric.

Fig. 10 is a view similar to Fig. 9 but with all the terry threads removed in order to show more closely the construction of the basic fabric and the location and arrangement of the weft threads.

Fig. 11 is a sectional view similar to Fig. 1 but showing the parts as located at the introduction of a terry thread.

Referring to the drawings in a more particular description it will be seen that the knitting machine is provided with a strong bed ring 15 rigidly supported in raised position by suitable supporting means (not shown) and that this bed ring rigidly supports thereabove in vertical and stationary position the needle cylinder 16 as by a projecting flange 17 on said ring receiving therewithin the lower end of said needle cylinder. Outside the flange 17 the bed ring 15 supports in rotatable fashion the carrier ring 18 which is rotated by means of its downwardly extending circle of teeth 19 being engaged by the teeth of gear 20 suitably mounted in an aperture of the bed ring 15 and driven by conventional means.

Resting upon the inner portion of the carrier ring 18 and fastened to rotate therewith there is provided the upstanding cam ring 21. On its inner side this cam ring is provided with suitable cams 22 providing upper and lower cam paths respectively 23 and 24 to cooperate with the heels 25 of the short needles 26 and the heels 25a of the long needles 27 respectively mounted in the alternate grooves of the needle cylinder as will be hereafter more particularly described.

From an overhead frame member of the machine (not shown) there depends a strong column 28 upon which adjacent its lower end there is supported within the upper part of the cylinder 16 a dial holder 29 supporting at its upper outer edge the dial 30. This dial is in the form of a flat ring having in its upper surface, upwardly opening and radially arranged slots 31

in which are slidably mounted the hooks 32. In the outward position of the hooks their outer ends project beyond the dial 30 between the upstanding shanks of the long needles 27 or of the short needles 26 and at their outer ends the downturned hooks 33 are attached to engage the terry yarn or thread 55 or 56 for the purpose of drawing loops of said terry thread inwardly between said up-raised needles.

Upon the carrier ring 18 outside of the cylinder cam ring 21 there are provided a plurality of upstanding, rigidly attached strong posts 35 upon the upper ends 36 of which there are mounted and secured the outer ends of the arms 37 of a spider-like frame 38, the center of which is vertically apertured to receive therewithin the hollow hub 39 of the dial cam holder 40. The central aperture of the hub 39 and of the dial holder 40 is mounted upon the depending stationary column 28 and rotates thereabout in unison with the cylinder cam 21 due to said dial cam plate 40 being carried by said spider member 38 which in turn is rotatably carried upon the upper ends of the posts 35, which are rigid with the ring carrier 18, which in turn as already mentioned carries the cylinder cam ring 21. On the lower horizontal surface of the plate 40 is provided and suitably secured the dial cam 41 having a cam path 42 opening downwardly to receive the upstanding butts 43 of the hooks 32 already mentioned as being slidably mounted in the dial 30.

From the upper ends 36 of the upstanding posts 35 there extend inwardly a plurality of brackets 44 which at their inner ends carry the yarn ring 45 spaced just outside the circle of the upper ends of the short needles 26 and the long needles 27 when in raised position. This mounting of the yarn ring causes said ring to be rotated in unison with the cylinder cam ring 21 and the dial cam 41 so that the different yarn or thread guides 46 which are mounted upon said yarn ring carry the said guides forward always at the proper relative position for the different threads of yarn to be supplied at each feed in the manner well known in this general type of circular knitting machine.

The needle cylinder and the two sets of needles are so constructed and arranged that the upper part of the shanks of one set of needles, preferably the long needles 27 will be slightly nearer the center of the cylinder than the corresponding upper part of the shanks of the other set of needles, that is the short needles 26. This allows the weft thread 46 to be laid against the outer edges of the upper part of the shanks of the up-raised long needles 27 (see Fig. 1) and yet allows the shanks of the short needles to thereafter ascend to upper position without cutting or breaking the weft thread located then immediately in front of the shanks of the long needles.

The needles of the two sets of needles alternate upon the cylinder and the machine is arranged to have the needles of the two sets brought into operating or knitting position and receive a stitch thread at alternate feeds, and this I accomplish by having the needles of the two sets operated each by its own separate cam path as by having the heels 25 of the short needles 26 operated by upper cam path 23 in a zone farther up than the zone of lower cam path 24 controlling the heels 25a of the long needles. The two cam paths of course are entirely separate and the width of the cam zone, 75

that is the vertical height of the zone on the cam ring, is such as to allow for the independent operation of the two sets of needles at alternate feeds. It follows from this that the short needles 26 at their operating feeds will receive one needle thread, while the other or long needles 27 at their feeds will receive the other needle thread.

The basic fabric thus knitted is shown in Figs. 9 and 10 of the drawings by the fabric composed of the two needle threads 47 and 48. Fig. 10 of the drawings shows most plainly the construction of this basic web in that the needle thread 47 shown in Figs. 9 and 10 as the more lightly shaded thread of yarn forms vertically extending rows of stitches having wales 49 connected by connecting legs 50 and the other needle thread 48, being the more darkly shaded needle thread, forms vertically extending rows of stitches having wales 51 connected by connecting legs 52 of said thread. The wales formed by either thread will alternate, that is as seen in Fig. 10, the wales 49 from thread 47 will be in the first and third rows counting from the right while the wales 51 from needle thread 48 will be in the second and fourth rows. Due to the knitting of the two needle threads at their separate alternate feeds neither thread will be drawn into the loops of the stitches of the other needle thread but the connecting legs of each thread will be caught into the junction points of the stitch loops of the other thread and so each connecting leg between the stitch loops of one needle thread will be drawn out of a straight line upwardly at its center by being caught into said connecting point of the other needle thread. There is thus formed by the connecting leg the diamond or lozenge shaped meshes 53 back of the stitch loops of the needle thread 47 and similar meshes 54 back of the stitch loops of the needle thread 48.

It will be seen that the wales of the stitches from both sets of needles and both sets of needle threads are upon the front of the fabric, that is the farther side as the fabric is shown in Figs. 9 and 10, and that all of the connecting legs of both sets of stitches are at the rear or loop side of the fabric.

In the preferred arrangement of this machine and in the arrangement proper to obtain the full fabric shown in Fig. 9 a loop or terry thread is fed into the fabric at each feed so as to provide a loop of the terry thread projecting out from the fabric at the rear side from each mesh. It is to be noted however that the same terry thread is not carried into all of the feeds but that one terry thread as 55 is fed in at the feeds of one set of needles and another terry thread 56, being the more darkly shaded terry thread shown in Fig. 9, is fed into the feeds of the other set of needles. These terry threads are led towards the needles by a guide 57 depending from the yarn ring 45 so as to dispose the terry thread at the front of the set of needles that is up-raised at that particular feed, it being understood that the other set of needles is at this time depressed. Immediately after the terry thread is thus placed in front of the upstanding needles at that feed the said terry thread is drawn back in loops between the shanks of the up-raised needles by the hooked ends 33 of the hooks 32 being drawn inward by the rotation of the dial cam 41. It will be noted that the drawing in of these long loops of terry thread by said hooks is done close enough to the feeding-in position of said terry

thread by yarn guide 57 as to draw the said terry thread through said guide in sufficient quantity to make the long loops of terry thread without unduly straining or stretching said terry thread. It will be understood that there is a drawing-in motion of the hooks 32 at each feed. The diagrammatic drawings Figs. 7 and 8 show most clearly the position of the terry threads as thus drawn in in loops between the up-raised needles at two feeds. In these views the right-hand feed shows the long or inwardly-located needles raised high and the short or outwardly-located needles depressed. At the succeeding feed or left hand feed of Figs. 7 and 8 the short needles will be in raised position and the longer needles in the lowered position and the other terry thread will be fed into that feed of the machine and drawn into loops between the shanks of the up-raised short needles in a similar way by the hooks 32. At the third feed the operation of the first feed will be repeated and at the fourth feed the operation of the second feed will be repeated. It follows from this that the terry thread 55 will have its loops 58 projecting out from the meshes 53 at the back of the stitches formed by the needle thread 47 and back of the vertical row of wales 49. Similarly the terry thread 56 will have its loops 59 projecting from the back of the fabric and from the other meshes 54 by the meshes back of the other needle thread 48 and its vertical chain of wales 51.

As already suggested the long needles 27 are so shaped and so mounted in the needle cylinder as to have the upper part of the shanks of these long needles nearer the center of the cylinder than the upper parts of the shanks of the short needles 26. The purpose of this is to allow the weft thread 46 to be laid against the outer side of the upper part of the shanks of the up-raised long or inwardly-located needles at the feed where the weft thread is to be introduced and still allow the short needles to be raised in front of said weft thread without cutting or breaking or displacing the weft thread. This slightly inward location of the upper parts of the shanks of the long needles is preferably and advantageously obtained by the construction which will now be described.

The outer face of the needle cylinder is provided with two different sets of needle grooves 60 and 61, with the grooves alternately arranged and shaped to house therein respectively the short needles 26 and the long needles 27. Both the short needles 26 and the long needles 27 used with this machine are preferably of the type where the lower half of the shank is of double width or depth, as by doubling the material from which the needles are made back upon itself so as to have a back or extra portion 62 upon the short needles and 63 upon the long needles and a front portion 64 upon the short needles and 65 upon the long needles. The front portion 64 of each short needle has the forwardly projecting heel 25 preferably and conveniently formed by a forwardly projecting loop made integral with the said front portion 64. Similarly the front portion 65 of the shank of the long needles has preferably integrally formed therewith its forwardly projecting heel 25a formed by a short compact loop bent into the material from which the needle is made. The upper portion 66 of the shank of the short needles is in line with the front portion 64 of the lower part of these needles. On the other hand the upper portion 67 of the shank of the

long needles is offset rearwardly to be in line with the rear or extra part 63 of the lower part of the shanks of the long needles.

A short distance down from the upper outer edge of the needle cylinder 16 the outer face of the cylinder has an inwardly extending depression or channel 68 deeper than the needle grooves which channel divides the needle grooves 60 and 61 into two horizontal zones, a narrow upper zone 69 and a lower, and wider or deeper zone 70. The deeper zone begins near the top of the cylinder cam 22 and extends to the bottom of the needle cylinder. The portion of both sets of needle grooves 60 and 61 which is in this lower and wider zone 70 is deep, that is it has enough depth to house the lower double-width portions of said needles with only the heels thereof projecting outside the needle cylinder into their respective cam paths in the cylinder cam 22. In the upper zone 67 of the cylinder the needle grooves are alternately deep and shallow to fit respectively the inwardly offset portion 67 of the long needles and the straight or non-offset portion 66 of the short needles. That is the portion of the needle groove 60 that is above the channel 68 is shallow or only deep enough to house the depth of the single thickness and non-offset portion 66 at the upper part of the short needles 26. On the other hand the portion of the groove 61 for the long needles, 30 that is above the interrupting channel 68, is cut or formed deeper in the face of the cylinder so as to receive the inwardly offset part 67 of these long needles 27. It will be obvious that the upper portion 67 will not occupy the whole of 35 the depth of the needle groove in this upper zone 69 but the needle will be slidably mounted in the rearward part of said groove.

Fig. 2 of the drawings, which is a top view of a part of the needle cylinder, clearly shows the shallow portion of the needle grooves 60 and the deep portion of the needle grooves 61 in the upper zone 69 of the needle cylinder.

Fig. 3, which is a sectional view through a part of the needle cylinder below the interrupting channel 68 and so through a part of the lower zone 70 of the needle cylinder shows that both the needle grooves 60 and 61 are deep through this part of the needle cylinder.

Fig. 4 shows the shape in side elevation of a short, viz. outwardly-located needle 26 and the housing of the doubled lower portion of its shank in the deep lower portion of its needle groove 60 and the housing of the narrow, single-thickness, straight portion 66 of its shank in the shallow part of the groove in zone 69 of the cylinder above the channel 68. In said view 4 the short needle is shown in its depressed position.

Fig. 5 shows a side elevation of a long needle and the housing of its doubled lower portion of the shank in the deep portion of its needle groove 61 in the lower zone 70 of the needle cylinder and also the location of the inwardly offset single thickness part 67, being the upper portion of the shank of the needle in the inner half of the deep upper portion of the needle groove 61 for these long needles. In Fig. 1 there is combined the showing of both Figs. 4 and 5 in that the short outwardly-located needle is shown depressed as in Fig. 4 in the immediate foreground and the long or inwardly located needle 27 is shown in raised position and in the next needle groove. The position of the needles and hooks in Fig. 11 is the position they occupy at the terry thread receiving point of a feed where a weft thread 46 75 is to be introduced. Accordingly the long in-

wardly-located needles 27 are in raised position and the short outwardly-located needles 26 are in depressed position so that the terry thread that is to be introduced at this feed can be brought to a line in front of the up-raised shanks of the said long inwardly-located needles 27 on a line below the hooks 32 so that the immediately following inward movement of the hooks 32 will cause the outer hooked ends 33 of said hooks to draw the said terry thread directly against the outer edges of the shanks of the needles 27 and draw sufficient yarn of said terry thread from the feed thereof so as to produce loops extending inwardly between each adjacent pair of raised needles 27. The inward projection of these loops 15 from the raised needles and the relative position of the retracted hooks is shown in Figs. 1 and 8. At this same feed and while the inwardly-located long needles 27 are still raised and while the outwardly located short needles 26 are still 20 in depressed position and particularly while the hooks 32 are still holding the loops of the terry thread projecting inwardly of the raised needles 27, the weft thread 46 is introduced and laid straight against the up-raised shanks of needles 25 27 as shown in Fig. 1. The relative position and shape of this weft thread 46 is shown in the diagrammatic view Fig. 8. It will be noted that this weft thread is laid in and stays in practically a straight line, that is on a large curve following 30 the periphery of the circle of the needles 27 as distinct from a serpentine formation that would result were both sets of needles operating on one and the same circle.

Very soon after the weft thread is thus laid 35 against the up-raised shanks of the inwardly located needles 27 the other or outwardly-located and herein called short needles 26 begin to ascend.

Fig. 1 is a detailed sectional view of the parts 40 adjacent the knitting point of the machine taken at a point soon after the short and outwardly-located needles begin to rise and when the hooks are holding the loops of terry thread inward. This view illustrates the important feature that 45 the weft thread is on the outside of the inwardly located needles 27 and that due primarily to the different radial location of the long needles 27 and the short needles 26 aided somewhat by the slight outward slant of the head of the short 50 needles, that is the part immediately above and below the needle latch 71, the said outward short needles can ascend outside of the said weft thread without breaking, straining, distorting or dislocating said weft thread. Preferably the weft 55 thread is relatively small and is laid in with sufficient tension to place and hold it straight against the shanks of the up-raised inner long needles 27. Accordingly any sliding contact of the back of the head or of the back of the shank of the 60 short needles while they are going up will not break, distort or strain the said weft thread. It will be understood that the needles are of such size and the inwardly located needles 27 have their upper portions located sufficiently inward 65 of the circle to be occupied by the upper parts of the shanks of the outwardly located or short needles 26 and the size and tension of the weft thread of yarn will be such as to allow the outwardly located needles to be raised in front of 70 the weft thread without injuring or materially displacing the weft thread.

It will be seen that the operation of the machine and its several parts has been to a considerable extent described incident to the de- 75

scription of the machine and its various parts already made. The operation of the several parts of the machine and particularly their contemporaneous operation of certain parts and the 5 operation of other parts in sequence may be clearly understood from an examination of the somewhat diagrammatic views Figs. 7 and 8. Fig. 7 is a developed front view of the needles and hooks at two feeds of the machine and Fig. 8 10 is a top or plan view of the hooks and needles for the same two feeds. The two views are to be considered together in that any given hook and any given needle is in alignment as nearly as may be in the two views. In both views the 15 right hand half of the view indicates what I will call for convenience the first feed, being a feed where a weft thread 46 is introduced as well as a needle thread as 47 and a terry thread as 55. About the left hand half of both Figs. 7 and 8 20 shows the position of the needles and hooks at the succeeding or what I will call second feed where the other needle thread 48 and the other terry thread 56 is introduced but without the introduction of a weft thread.

25 It will be understood that in this machine the parts are organized and assembled to have the needle-operating cams and the hook-operating cams and the various thread or yarn guides all rotating to the right past the non-rotating 30 needles and hooks.

At the extreme right hand portion of Fig. 7 which represents the part of the machine just before the first feed it will be seen that both the long or inwardly-located needles 27 and the short 35 outwardly-located needles 26 are in the extreme upward position. By reference to the corresponding part of Fig. 8 it will be seen that the hooks 32 are in inward position with their extremities relatively close to the hook dial 30 and 40 inside of even the inwardly-located needles 27.

Throughout this first feed as will be seen in Fig. 7 the long inwardly located needles 27 remain at their extreme upward position and do not perform a knitting operation, but of course 45 are retaining about their shanks approximately at the level of the upper edge of the needle cylinder the loops from the last preceding stitches made by these needles 27. On the other hand the short or outwardly-located needles 26 at the 50 beginning of this first feed begin to descend and soon receive as at point 12 the needle thread 47 supplied by the conventional thread guide therefor. Further downward movement of these short needles 26 carries downwardly the said needle 55 thread 47 caught in the hooks or eyes of the said short needles until as the short needles descend far enough the new loops of the needle thread 47 are drawn through the old loops upon these short needles and the old loop is cast off in the 60 manner common to this type of knitting machines and not necessary to be further described herein. Meanwhile as will be seen by reference to the corresponding part of Fig. 8, the hooks 32 have been pushed forward between the up-raised inward 65 needles 27 and past the now depressed short outward needles until a hook is at its outward limit of movement. At about this point as at thread outlet 73 in Figs. 7 and 8 provided in the terry thread guide 57 the terry thread 55 is introduced 70 as most clearly shown in Fig. 11 at a point below the shank of the outwardly-thrust hook but with in the down-turned hook-end of said hook. Immediately thereafter the inward travel of the hooks is brought about as appears most plainly 75 from Fig. 8 and this draws back the said terry

thread 55 not only against the upstanding shanks of the long up-raised needles 27 but ultimately draws loops of said terry thread 55 projecting inwardly from the shanks of adjoining long inwardly-located needles 27.

At about the time when the hooks have withdrawn to inward position each carrying a loop of the terry thread therewith as just mentioned, the weft thread 46 is introduced. The position of the parts at this time is indicated clearly in 10 the main drawing Fig. 1. It will be seen that through eyelet 74 on the weft thread guide 75 the said weft thread is delivered to a point closely in front of the up-raised shanks of the inward needles 27. At this point as seen 15 in Figs. 1 and 8 the loops of the terry thread are shown slightly farther down on the needles 27 as still held inwardly by the hooks 32. This weft thread is laid in with sufficient tension to hold it practically straight across the said up-raised needles 27 so that as the short needles 26 which are the outwardly-located set of needles, commence and continue their upward movement, the heads of the said short needles will not push said weft thread upwardly but will rise 20 25 closely in front of said weft thread and leave the said weft thread in practically a straight line, that is, in one long curve corresponding to the diameter of the circle of needles, but with the weft thread between the up-raised short needles 30 35 on the outside and the up-raised long needles on the inside. If the outer set of needles 26 have their inner edges only about in line with the outer edges of the inner needles 27 and the weft thread is of small size, this straight line or long 40 45 curve of the weft thread will be interrupted with only slight curves as it goes between the two sets of needles. Obviously if the two sets of needles are not separated so far or if the weft thread is of considerable size the said thread will 50 55 have a more undulating or serpentine shape, but the machine should be so constructed as to put a minimum of undulations in this weft thread in order to allow the machine to work as outlined and also in order to allow the weft thread 45 to have so little slack or curve when placed in the fabric as to render the fabric practically inelastic transversely of the wales after the finishing stretching operations have been performed 60 upon the fabric.

It will be seen that at about the center of Figs. 7 and 8 the short outer needles 26 have risen to the extreme upward position and thereafter stay in that position for the next or second feed, being the portion represented in the left hand part of 55 Figs. 7 and 8. Soon after the outward or short needles 26 have risen to this upward position the long needles 27 begin their descent and receive as at feed eyelet 16 the needle thread 48. As 60 these inner long needles descend the forward or outward inclination of their heads catch this needle thread 48 and draw loops therein which by the time the long needles come to their lowermost position have drawn these new loops through the old loops upon the shanks of the said long needles 65 and have cast off the old loops. Before this casting off operation has occurred, however, the weft thread 46 and the terry thread 55 carried along from the previous feed have been cast over the tops of the descending long needles without going into the eyes of said needles and thus have completed the laying of the said terry thread 55 and the weft thread 46 into the fabric without its being knitted into the stitches of the fabric. 70 75

- By the time the long inner needles 21 have reached their lower position the hooks 32 have been again extended so as to bring a hook to its extreme outward position and engage the terry thread 56 introduced at this feed from feed eyelet 5. The needles are then in the relative position as shown in Fig. 6 and therefore the immediately following inward movement of the hooks 32 carry this terry thread back against the front of the shanks of the short outer and up-raised needles 26 and on the further withdrawal of the hooks draw terry loops extending backward or inwardly from the shanks of said raised needles. Due to the fact that no weft thread is placed into the machine at this feed it will be seen that the long needles 21 can thereafter commence and complete their upward movement without disturbing the terry loops since the said loops are drawn taut against the front of the said up-raised short needles and between each adjacent pair of short needles the terry loops are still held back by the hooks 32 so that space is provided for the upward movement of the long needles. At the third feed the terry thread introduced at the second feed gets permanently placed into the fabric and otherwise all the operations mentioned for the first feed are repeated at the third feed. The fourth feed repeats the operations of the second feed and so on indefinitely.
30. What I claim as new and desire to secure by Letters Patent is:
1. In a circular, independent-needle knitting machine the combination of a vertically arranged stationary needle cylinder having alternate needle grooves adapted to carry the needles therein and their upwardly projected shanks in two spaced concentric circles, two sets of needles having their several needles independently and reciprocatingly mounted in said respective sets of grooves, each needle carrying its upwardly projecting shank at a fixed distance from the axis of the cylinder at all vertical positions of the needles, means for knitting with the alternate set of needles at alternate feeds, means for raising the non-knitting needles at a given feed up to have their shanks above the heads of the needles knitting at that feed, a dial stationarily located within the upper part of the cylinder and having radially arranged slots at its outer part, hooks having down-turned outer ends slidingly mounted in said dial slots, means for projecting and withdrawing said hooks between the shanks of said upraised non-knitting needles, means for guiding a terry thread into place in front of the shanks of the said upraised needles, and below the projected hooks whereby the inward movement of the hooks draws said terry thread into loops projecting inwardly between the upraised shanks of the needles, means at the feeds where the inner set of needles have their shanks raised above the heads of the other set of needles for laying a weft thread substantially straight against the shanks of said upraised inner needles and means for then raising the outwardly-located needles in front of the said straight weft thread with no substantial distortion thereof.
  2. In a circular independent-needle knitting machine the combination of a vertically arranged stationary needle cylinder having the needle grooves alternately shallow and deep to carry the needles therein and their upwardly projecting shanks in two spaced concentric circles, two sets of needles having their several needles independently and reciprocatingly mounted in said respective shallow and deep sets of grooves, each

needle carrying its upwardly projecting shank at a fixed distance from the axis of the cylinder at all vertical positions of the needles, means for knitting with the alternate set of needles at alternate feeds, means for raising the non-knitting needles at a given feed up to have their shanks above the heads of the needles knitting at that feed, a dial stationarily located within the upper part of the cylinder and having radially arranged slots at its outer part, hooks having down-turned outer ends slidingly mounted in said dial slots, means for projecting and withdrawing said hooks between the shanks of said upraised non-knitting needles, means for guiding a terry thread into place in front of the shanks of the upraised non-knitting needles, and below the projected hooks whereby the inward movement of the hooks draws said terry thread into loops projecting inwardly between the upraised shanks of the needles, means at the feeds where the inner set of needles have their shanks raised above the heads of the other set of needles for laying a weft thread substantially straight against the shanks of said upraised inner needles and means for then raising the outwardly-located needles in front of the said straight weft thread with no substantial distortion thereof.

3. In a circular, independent-needle knitting machine the combination of a vertically arranged stationary needle cylinder having vertically arranged needle grooves, needles independently and slidingly mounted in said grooves, the alternate needles forming two independently-operable sets of needles having their upwardly projecting shanks in two spaced concentric circles, each needle carrying its upwardly projecting shank at a fixed distance from the axis of the cylinder at all vertical positions of the needles, the needles of the first set having the part of their shanks that is above the cylinder when the needles are raised, located inwardly relative to the same part of the shanks of the second set of needles when raised so that a weft thread can be placed in front of the upraised inwardly-located needles and remain there without injury or substantial displacement when the outwardly located needles are raised, means for knitting with the alternate set of needles at alternate feeds, means for raising the non-knitting needles at a given feed up to have their shanks above the heads of the needles knitting at that feed, a dial stationarily located within the upper part of the cylinder and having radially arranged slots at its outer part, hooks having down-turned outer ends slidingly mounted in said dial slots, means for projecting and withdrawing said hooks between the shanks of said upraised non-knitting needles, means for guiding a terry thread into place in front of the shanks of the said upraised needles, and below the projected hooks whereby the inward movement of the hooks draws said terry thread into loops projecting inwardly between the upraised shanks of the needles, means at the feeds where the inner set of needles have their shanks raised above the heads of the other set of needles for laying a weft thread substantially straight against the shanks of said upraised inner needles and means for then raising the outwardly-located needles in front of the said straight weft thread.

4. In a circular independent-needle knitting machine the combination of a vertically arranged stationary needle cylinder having vertically arranged needle grooves, the lower part of said grooves being deep and the upper parts of said grooves being alternately deep and shallow,

needles independently and slidingly mounted in said grooves, the alternate needles forming two independently operable sets of needles having their upwardly projecting shanks in two spaced concentric circles, each needle carrying its upwardly projecting shank at a fixed distance from the axis of the cylinder at all vertical positions of the needles, the needles of the first set having their intermediate and upper portions mounted in the said upper deep cylinder grooves, the needles of the second set having their intermediate and upper portions farther front than the first set and fitting said shallow upper grooves so that a weft thread can be placed in front of the upraised inwardly-located needles and remain there without injury or substantial displacement when the outwardly-located needles are raised, means for knitting with the alternate set of needles at alternate feeds, means for raising the non-knitting needles at a given feed up to have their shanks above the heads of the needles knitting

at that feed, a dial stationarily located within the upper part of the cylinder and having radially arranged slots at its outer part, hooks having down-turned outer ends slidingly mounted in said dial slots, means for projecting and withdrawing said hooks between the shanks of said upraised non-knitting needles, means for guiding a terry thread into place in front of the shanks of the upraised non-knitting needles, and below the projected hooks whereby the inward movement of the hooks draws said terry thread into loops projecting inwardly between the said upraised shanks of the needles, means at the feeds where the inner set of needles have their shanks raised above the heads of the other set of needles for laying a weft thread substantially straight against the shanks of said upraised inner needles and means for then raising the outwardly-located needles in front of the said straight weft thread.

JOHN H. MURPHY.
